UNITED STATES PATENT OFFICE.

ASSER J. BENJAMINS, OF BROOKLYN, NEW YORK.

DEVICE FOR HOLDING PRECIOUS STONES.

1,371,840.

Specification of Letters Patent. Patented Mar. 15, 1921.

Application filed January 10, 1920. Serial No. 350,520.

To all whom it may concern:

Be it known that I, ASSER J. BENJAMINS, a citizen of the United States, and a resident of Brooklyn, borough of Brooklyn, county 5 and State of New York, have invented a new and Improved Device for Holding Precious Stones, of which the following is a full, clear, and exact description.

This invention relates to an apparatus 10 used in connection with the cutting of precious stones and has particular reference to a device for holding precious stones.

The invention contemplates and has for its principal object the provision of a device 15 for holding stones with which a gage for determining the correct axle of the facets may be used without the necessity of removing the same therefrom.

Another object of the invention is to materially 20 improve devices of this character in order to render the task of properly cutting and gaging the stone comparatively simple in comparison with methods now employed.

A further object of the invention is to provide 25 an improved holding and retaining means for a stone which will accommodate gems of various sizes without the necessity of changing the equipment and which provides means with which a suitable gage may 30 be engaged to obtain the proper angularity of the bottom facets.

With the above recited and other objects in view, some of which will be more apparent hereafter, reference is made to the following detailed description, the appended claims and accompanying drawings forming a part of this application, in which:

Figure 1 illustrates a side elevation of 40 standard and well-known appurtenances used in the diamond cutting art, and to which the device constituting this invention is applied.

Fig. 2 illustrates a cross sectional view 45 taken through a chuck or clamp used for holding a diamond in position while operated on by a cutting wheel.

Fig. 3 shows a diamond holder constructed in two parts drawn to show the parts 50 in separate relation.

Fig. 4 illustrates an adjustable protractor of well-known design shown in service position, during the act of measuring the angle on the facet of a stone.

55 In presenting a more detail description of the invention there is shown in the draw-

ings a stone holder comprising a shank 9 and a cup 10. The shank is tapered on the longer end to tightly fit into a socket of a chuck. The upper end of this shank is likewise tapered to fit into a socket 11 made in the cup 10. The socket 11 is made the counter-part of the shorter tapered end of the shank 9 so that the cup may be tightly thrust and anchored in position on the top end of 65 the shank to form a stone holder 9-10. The cup 10 is made to retain the diamond while a device as later explained, is used to clamp this diamond in the cup. The cup is made in the form of a cylinder, and has 70 a peripheral rim 12. A sector of the rim 12 is removed to form a notch or opening in the cup to more readily expose the facet of the diamond on the side of the cup in which the notch is made. The rim 12 projecting above the top face of the cup leaves a plane face 14 which acts as a base to seat the stone in position while being ground. The table or face 14 is formed on a plane 75 right angular with the axis of the cup and shank so that a stone clamped in position in the cup and properly seated therein, with no dust or grit particles between the stone and cup, occupies a correct position relatively to the stone holder 9-10.

In the Figs. 1, 2 and 4 there is shown a stone, such as a diamond 18, clamped into position within the cup 10 of the stone holder. A cup 10 has been selected in accordance with the diametral size of the girdle and top facet 90 of the diamond. The stone 18 is then clamped into position with the table and top facet placed in contact with the face 14 and rim 12 of the cup. This maintains the axis of the stone 18 coincident with the axis of the 95 stone holder so that the stone occupies a position relatively correct to the stone holder.

The stone holder 9-10 is mounted in a diamond cutter's chuck 19 by thrusting the shank 9 into a socket made in the chuck for 100 the reception of the tapered shank. The diamond cutter's chuck is usually fitted with a bifurcated clamp jaw 20, or jaw of other appropriate type, which moves inwardly and outwardly relatively to the chuck for 105 engagement with the stone 18 mounted in the stone holder. The jaw 20 is usually fixed to a sliding shank 21 having an appropriate clamp screw to jam against the sliding shank 21 to fix the jaw 20 against the stone 18 for 110 anchoring the stone in locked position between the jaw and stone holder. A chuck

stem 22 is fixed in the chuck to mount it in a vise arm 23 on the diamond cutter's work-table to receive the chuck and hold it in service position relatively to the grinding and 5 polishing wheel 24.

As is well known to those skilled in the art, the bezels, corners and pavilions are cut on the face of the diamond by holding the diamond against the grinding wheel 24 and 10 accurately cutting the diamond until the proper angularity is obtained. Each and every separate corner and pavilion on the face must be individually ground; therefore it necessitates a great deal of measuring to 15 determine when the proper angle has been reached.

An adjustable protractor comprises a protractor blade 26 pivotally mounted in a protractor frame 27. The frame has the clamp screw 28 which tightens the frame on the protractor blade 26 to maintain the correct 20 setting of the instrument. The inner end 29 of the protractor frame 27 is vertically true so that it may be applied against the outer cylindrical face of the diamond holding cup 10. The outer surface edge of the protractor blade 26 then becomes alined with the facet of the stone, and if the plane edge 25 of the protractor is coincident with the plane 30 of the facet the diamond cutting mechanic then knows that the facet being measured is accurately ground and the stone is remounted in the cup for the next cutting operation.

35 Fig. 4 shows the manner of applying the protractor against the stone holding cup 10 and the diamond 18. The plane vertical end 29 of the protractor is placed against the cup and the line indicating the protractor edge lies coincident with the line indicating the facet of the diamond. It is seen therefore that the diamond 18 in Fig. 5 is ground accurately, as far as the angularity of the particular facet being ground is concerned. 40 In case the angularity of the facet is not correctly ground the protractor edge and the facet edge will not lie parallel. This condition is readily detected by the observing eye of the diamond cutter when he notes light 45 passing between the facet and the protractor. The stone is then returned to the grinding wheel and a little more of the stone is carefully ground away until the correct angle is obtained.

50 In taking measurements, the diamond cutter usually lifts the chuck 19 and vise from the wheel in order to get sufficient light on

the device. It is never necessary for a mechanic to remove the stone 18 from the cup for the reason that the diamond cup used in combination with the protractor may be brought together to effect the desired measurements. This particular accomplishment and faculty of the appurtenance constituting this invention makes for economy and 60 efficiency in practising the art.

Having thus described my invention, I desire to secure by Letters Patent:

1. In a device of the character described, means for supporting a stone from a chuck for cutting the bottom facets thereof, said means including a flat base to receive the table facet of the stone and a right angularly disposed wall affording a base with which a protractor gage is adapted to co-act for gaging the proper uniform angularity of the bottom facets without the necessity of removing the stone therefrom. 70

2. In a device of the character described, a stone receiving member having a flat outer end wall and an outer side wall disposed at right angles to said end wall, and means for retaining the table facet of the stone in operative contact with the end wall, the said side walls constituting a base with which the stationary frame member of a protractor gage is adapted to co-act for obtaining the proper uniform angularity of the bottom facets without the necessity of removing the stone from the receiving member. 75

3. In a device of the character described, a cylindrical stone receiving member having an end wall at a right angle to the longitudinal axis thereof, an annular side wall, the outer surfaces of the end and side walls 95 being disposed at a right angle to each other, and a semi-annular peripheral flange projecting from said end wall, as and for the purpose set forth. 90

4. In a device for supporting precious stones for cutting the bottom facets, a cylindrical stone receiving member having a solid end wall at a right angle to its annular side wall, an annular flange on said end wall having an open side, the said end wall and 105 means clamping the table facet of the stone against said end wall, the said side wall affording a base with which a protractor gage may co-act to obtain the proper uniform angularity of the bottom facets without the necessity of removing the stone therefrom. 110

ASSER J. BENJAMINS.
